UNITED STATES PATENT OFFICE.

ALBERT W. PEARSALL, OF LOWELL, MASSACHUSETTS, ASSIGNOR TO LAMSON CONSOLIDATED STORE SERVICE COMPANY, OF NEWARK, NEW JERSEY, A CORPORATION OF NEW JERSEY.

PNEUMATIC-DESPATCH-TUBE APPARATUS.

1,032,155.

Specification of Letters Patent.

Patented July 9, 1912.

Application filed May 11, 1906. Serial No. 316,290.

To all whom it may concern:

Be it known that I, ALBERT W. PEARSALL, of Lowell, in the county of Middlesex and State of Massachusetts, have invented certain new and useful Improvements in Pneumatic-Despatch-Tube Apparatus, of which the following is a specification.

My invention relates to improvements in pneumatic despatch tube apparatus and its object is to control the flow of air through the transmission tubes so that power may be used only to effect the actual transmission of the carriers. This device is designed to operate independent of the power used in the transmission of carriers and may be actuated primarily by an electric circuit and secondarily through the medium of any fluid under pressure. Unlike the usual devices of this kind, this apparatus permits of the control of the flow of air in the transmission tube either below or above atmospheric pressure with more positive and greater range of regulation.

In the accompanying drawings which illustrate a construction embodying my invention, Figure 1 shows the device in elevation and in connection with a vacuum pneumatic tube system. Fig. 2 is an enlarged detail sectional view of part of the mechanism.

Like letters of reference refer to like parts throughout the several views.

The transmission tube A having the usual bell mouth A' is connected with the upward discharge terminal A² with the usual discharge valve A³; connecting said terminal A² with the downward discharge terminal B' is the transit tube B having at its upper end an inlet for carriers controlled by the valve B² of common construction in the art.

Connecting the downward discharge terminal B' with the upper chamber C of the casing D is the tube C', the lower chamber C² being connected with the drum C⁴ by the pipe C³. Controlling the passage between the chamber C² and C is the valve D' normally closed. Allowing for the upward movement of said valve is the hood D² mounted on the upper part of the casing D. The valve D' is affixed to the hollow spindle

D³ at its upper end and at its lower end the spindle is attached to the piston D⁴ adapted to reciprocate in the cylinder D⁵ attached to the lower portion of the casing D.

Mounted within the hollow spindle D³ is the movable connecting rod E carrying on its upper end the cap E' and pivotally connected at its lower end with the rock lever E² which is centrally pivoted in the yoke E³ which also forms the lower head of the cylinder D⁵. To the opposite end of the rock lever E² is pivoted the connecting rod E⁴ carrying the valve pistons F and F' mounted within the valve cylinder F² which is connected by the passage F³ with the lower end of the cylinder D⁵.

To the upper end of the connecting rod E⁴ supported in the bearing F⁴ is attached the armature F⁵ adapted to be operated by the magnet F⁶, the coils of which are connected with the switches G and G' by the line wire G² and G³, the battery G⁴ furnishing current to said magnet.

Connecting the upper part of the valve cylinder F² with a source of water pressure H is the passage H' controlled by the valve piston F'. Connecting the lower part of said valve cylinder F² with the outlet J is the passage J' controlled by the piston valve F. Controlling the passage J' is a hand operated valve J² for graduating and timing the exhaust of the water.

In operating the device the switch G' is momentarily closed energizing the magnet F⁶ attracting the armature F⁵ which causes the valves F and F' to move upward closing the passage J' and opening the passage H' admitting water under pressure into the cylinder D⁵ and forcing the piston D⁴ upward lifting the valve D' and permitting the vacuum in the chamber C² to enter the system. The carrier is now inserted into the bell mouth A', drawn through the transit tube A and discharged through the terminal valve A³. In the meantime, the water pressure having forced the piston D⁴ to its extreme limit of travel, said piston engages the cap E' and through the medium of the rock lever E² draws down the valves F and F' closing the passage H' to the

water pressure and opening the timing passage J' for the gradual escape of water, allowing the piston D^4 and valve D' to drop by gravity to normal or closed position, thereby cutting off the circulation of air. It will be readily seen that as often as the circuit is closed the above operation will be repeated. Carriers may be despatched from the despatch inlet B^2 to the terminal 10 B' in similar manner.

Having thus described the nature of my invention and set forth a construction embodying the same, what I claim as new and desire to secure by Letters Patent of the 15 United States is:

1. In pneumatic despatch tube apparatus, an exhaust chamber, a transit tube communicating with said exhaust chamber, a valve controlling the communication between the exhaust chamber and the transit tube, a fluid-pressure motor for operating said valve, a supply pipe leading to said motor from a source of fluid-pressure separate and distinct from the fluid-pressure in 20 the exhaust chamber and transit tube, a discharge pipe leading from said motor, a valve controlling the communications between the motor and the supply and discharge pipes, electric means for actuating the last mentioned valve to open the motor to the supply pipe and to close it to the discharge pipe to effect the opening of the valve controlling the communication between the exhaust chamber and the transit tube, and mechanism actuated by said motor as the latter approaches the limit of its valve-opening operation for reversing the valve controlling the supply and discharge pipes so as to close the motor to the supply pipe and to open it 25 to the discharge pipe to effect the closing of the valve controlling the communication between the exhaust chamber and the transit tube.

2. In pneumatic despatch tube apparatus, an exhaust chamber, a transit tube communicating with said exhaust chamber and extending to a plurality of stations, an air-valve controlling the communication between the exhaust chamber and the transit tube, a cylinder, a piston movable in said cylinder connected with said air-valve, a supply pipe leading to said cylinder from a source of fluid-pressure separate from said exhaust chamber, a discharge pipe leading 30 from said cylinder, a fluid-pressure valve controlling the communications of said supply and discharge pipes with the cylinder, an electric circuit including a source of electricity extending to the different stations, a switch at each station to control the electric circuit, a magnet in the electric circuit for operating the fluid-pressure valve to close said discharge pipe and to open said supply pipe to admit fluid-pressure into the cylinder.

3. In pneumatic despatch tube apparatus, an exhaust chamber, a transit tube communicating with said exhaust chamber, an air-valve controlling the communication between the exhaust chamber and the transit tube, a cylinder, a piston movable in said cylinder connected with said air-valve, a supply pipe leading to said cylinder from a source of fluid-pressure separate from said exhaust chamber, a discharge pipe leading from said cylinder, a fluid-pressure valve controlling the communications of said supply and exhaust pipes with the cylinder, means for operating said fluid-pressure valve to close said discharge pipe and to open said supply pipe to admit fluid-pressure into the cylinder to move the piston to open said air-valve, and mechanism actuated by said piston as the air-valve approaches the limit of its opening movement for operating the fluid-pressure valve to close the supply pipe and to open the discharge pipe to free the cylinder of the fluid-pressure to permit the piston to move to close the air-valve.

4. In pneumatic despatch tube apparatus, an exhaust chamber, a transit tube communicating with said exhaust chamber, an air-valve controlling the communication between the exhaust chamber and the transit tube, a cylinder, a piston movable in said cylinder connected with said air-valve, a supply pipe leading to said cylinder from a source of fluid-pressure separate from said exhaust chamber, a discharge pipe leading from said cylinder, a fluid-pressure valve controlling the communications of said supply and exhaust pipes with the cylinder, means for operating said fluid-pressure valve to close said discharge pipe and to open said supply pipe to admit fluid-pressure into the cylinder to move the piston to open said air-valve, mechanism actuated by said piston as the air-valve approaches the limit of its opening movement for operating the fluid-pressure valve to close the supply pipe and open the discharge pipe to free the cylinder of the fluid-pressure to permit the piston to move to close the air-valve, and means to regulate the outflow of the fluid-pressure through the discharge pipe to time the closing of the air-valve.

5. In pneumatic despatch tube apparatus, an exhaust chamber, a transit tube communicating with said exhaust chamber, an air-valve controlling the communication between the exhaust chamber and the transit tube, a cylinder, a piston movable in said cylinder, a hollow spindle connecting the piston with the air-valve, a valve-casing opening intermediate of its ends into said cylinder, a supply pipe leading to one end of said valve-casing from a source of fluid-pressure separate from said exhaust chamber, a discharge pipe leading from the other end of the valve-casing, valve-pistons in said valve-casing to control the communications of said supply and discharge pipes through the valve-casing with the cylinder, means for moving said valve-pistons to close said discharge pipe and to open said supply pipe to admit fluid-pressure to the cylinder to move the piston therein to open said air-valve, a pivoted lever connected at one end with said valve-pistons, a rod connected with the other end of said lever passing into said hollow spindle, a cap on the inner end of said rod to engage said piston when the air-valve approaches the limit of its opening movement to move said rod to actuate said lever to move the valve-pistons to open the cylinder.

discharge pipe and to close the supply pipe to relieve the cylinder of the fluid-pressure to permit the piston to move to close the air-valve, and means to regulate the out-flow of fluid-pressure through the discharge pipe to time the closing of the air-valve.

5 In testimony whereof, I have signed my

name to this specification in the presence of two subscribing witnesses, this 8th day of May A. D. 1906.

ALBERT W. PEARSALL.
